HOLDING DEVICE

Donald A. Boylan, Erwin Township, Steuben County, N.Y., assignor to Westinghouse Electric Corporation, East Pittsburgh, Pa., a corporation of Pennsylvania
Filed May 21, 1962, Ser. No. 196,119
5 Claims. (Cl. 140—71.5)

The present invention relates to devices for winding grid electrodes for use in electron tubes and, more particularly, to a holding means adaptable to standard grid machines for slidably retaining the frame strip of a frame type grid at a point near which the grid is being wound.

In the winding of conventional grids, that is, notched and peened grids having only side rods with grid laterals wound thereon, the side rods slide individually through holes or grooves in a mandrel which is held by the rotating lathe head or spindle. In the case of frame grids, however, this method will not work as the presence of cross members between the side support rods prevents the side rods from being held individually.

The prior art method of winding a strip of frame grids employed a technique whereby the grid strip was clamped at its extreme ends in a carriage, and the strip and its carriage were traversed past the winding point. Alternatively, the winding point was made to traverse the length of the grid strip. By either technique, the strip was unsupported in its center portion when lateral wire was being wound on this portion of the strip. Therefore, the strip length was largely limited by the mechanical strength of the strip in its ability to resist the bending force of the lateral wire tension rather than by machine or other considerations.

In a copending application assigned to the assignee of the present invention, titled "Frame Grid Holding Apparatus" by William H. Simmonds, Serial No. 196,123, filed May 21, 1962, there is described a guide for slidably maintaining a grid strip of the frame type. The guide provides briefly, that the grid strip is maintained between two adjustable jaws which are mounted on a suitable base member. While this guide is much more satisfactory than the prior art, there is a possibility that the use of this guide may upon occasion, permit a certain amount of vibration of the grid strip in the jaw members. This vibration is due to the fact that the distance between the jaws must be set to the maximum dimensions of the strip (plus clearance) and that a slight reduction in these dimensions would result in the grid strip being somewhat loosely held at the reduced dimension points.

It is, therefore, an object of this invention to provide an improved means for adapting standard grid winding machines to the winding of frame type grids.

Another object is to provide an improved holding device for use in the winding of frame grids.

A further object is to provide an improved means for securely holding a frame grid strip in a slidable manner.

Briefly, the present invention provides a holding means for slidably retaining a frame grid strip. The holding device may be mounted on the rotating spindle or head of any convenient grid winding machine or it may be maintained stationary. In either case, the grid strip is gripped at one end and drawn through the holding device which includes resilient means acting upon the grid strip in planes mutually transverse to each other to maintain the grid strip in firm contact with two reference surfaces. The winding station or point may be positioned closely adjacent the holding device and thus the device serves to support the strip against the bending occasioned by the winding of the grid laterals and to reduce this bending to a negligible amount. Thus the total length of grid strip

2

which may be utilized is limited largely by machine design and handling considerations.

Further objects and advantages of the invention will become apparent as the following description proceeds and features of novelty which characterize the invention will be pointed out in particularity in the claims annexed to and forming a part of this specification.

For a better understanding of the invention, reference may be had to the accompanying drawings, in which:

FIGURE 1 is a front plane view of a holding device in accordance with the present invention;

FIG. 2 is a side elevational view of the device of FIG. 1; and,

FIG. 3 is a side elevational view of one of the resilient or spring members of the device of FIG. 1.

Referring now to FIGS. 1 to 3, there is shown a device for holding a frame grid strip in accordance with the present invention. The embodiment shown is one of convenient design which is adapted for mounting on the rotating head or spindle of a conventional grid making machine, for example a lathe such as that described in United States Patent No. 2,441,228, issued May 11, 1948.

The device comprises a base member 12 which serves as a suitable platform to which a support member 30 is attached. The base 12 is preferably cylindrical in shape, of a suitable material such as steel, and is provided with a rearwardly extending portion 16 which may be press-fitted into a hollow rotating spindle of the grid winding machine. The base 12 is also provided with a centrally extending bore 20 to permit the longitudinal passage of the frame grid strip therethrough.

In FIG. 2, there is shown a frame grid strip 22 of the type for which the present invention is designed. The end view of this strip 22 may be seen in FIG. 1. The strip 22 comprises a pair of support or side rods 24 which are held in a spaced relationship by a plurality of cross bars 26. The cross bars 26 are affixed to the side rods 24 by a suitable means such as welding. The strip 22 is prefabricated prior to the winding of the grid laterals in a manner well known in the art.

A suitable recess 28 is provided in the top surface of the base member 12. A support member 30 is disposed within the recess and is affixed to the base member by a suitable means, for example a pair of bolts 32 which extend longitudinally through the support member 30 and are secured in the base member 12. One side of the support member 30 is provided with an offset portion indicated generally at 40 and the member 30 is placed so that the offset portion 40 is positioned over the centrally extending bore 20 of the base member 12. The offset portion 40 provides a first fixed surface 42 and a second fixed surface 44 which are positioned in planes substantially perpendicular to one another and extend longitudinally the length of the member 30. As has been stated, the offset portion 40 is positioned substantially over the centrally extending bore 20 and the fixed surfaces 42 and 44 serve as fixed references against which the grid strip 22 is maintained in a slidable fashion.

The fixed surface 42 provides the fixed reference surface against which the cross members 26 of one side of the grid strip 22 are maintained. The side rods 24 of the grid strip 22 have as their fixed reference surface the second fixed surface 44. A suitable recess 46 is provided between the fixed surfaces 42 and 44 so that even though the cross bars 26 of the grid strip 22 extend slightly beyond the side rods 24, they do not touch the fixed surface 44. In a like manner, the fixed surface 44 is provided with a beveled edge 48 so that the cross bars on the other side of the side rods 24 do not touch the fixed surface 44. Thus, in the preferred embodiment, the fixed surface 44 has a width smaller than the diameter of the side rods 24.

and this surface 44 is in contact with substantially only one side rod 24 of the grid strip 22.

The grid strip 22 is held firmly against the fixed surfaces 42 and 44 by means of two resilient or spring members 50 and 60 which are secured to the support member 30. The first resilient member 50 acts upon the upper side rod 24 of the frame grid strip 22 to maintain the strip against the fixed surface 44. The resilient means 50 is preferably comprised of a spring wire member having one end 52 thereof secured to the support member 30. The other end 56 of the wire member 50 is of substantially U-shaped configuration and is positioned about a stud member 58 which is affixed to the support 30 in a manner to limit the movement of the free end 56 of the member 50. A fulcrum 54 is positioned intermediate the ends 56, 52 of the member 50 in a manner to bias the member 50 in a downwardly direction. The member 50 has a diameter preferably not exceeding that of the side rods 24, and its action is substantially only on upper side rod 24 to maintain the lower side rod 24 in contact with the fixed surface 44.

The second resilient or spring means 60 may best be seen in FIGS. 2 and 3. The resilient means 60 is comprised of a main portion 62 and two leg portions 64 and 66. The member 60 is provided with one or more holes 67 in its lower portion and is secured to the support member 30 by means of suitable fastening means, for example bolts 68. The leg 64 is bent from the plane of the rest of the member 60 at 63 to provide that the outer portion 65 of the leg 64 lies in a plane substantially parallel but slightly displaced from the plane of the body portion 62 of the member 60. The leg 64 is preferably slightly smaller in width than the width of the grid strip 22 and also has a length sufficient to span, at any one time, a plurality of cross bars 26 of the grid strip 22. The member 60 is supported by the support member 30 and is positioned so that the distance between the fixed surface 42 and the leg portion 65 is slightly less than the thickness of the cross bars 26 and the side rods 24 combined. In this manner, the resilient member 60 serves to maintain the grid strip 22 firmly against the fixed surface 42.

In the winding operation, one end of the grid strip 22 is attached to suitable means, such as a draw bar, which provides the strip 22 with both rotary motion about and linear motion along its longitudinal axis. The lathe spindle, and hence the holding device of the present invention, which is secured to the spindle, is rotated at a speed synchronous with that of the draw bar. A suitable means 70 for directing the grid lateral wire 72 onto the strip 22 is positioned at a point near to the free end of the support member 30. Thus, as the grid laterals are drawn on to the rotating strip 22, the holding device of this invention provides the requisite support to prevent the bending of the strip 22.

In the preferred embodiment, each of the resilient means 50 and 60 exert approximately one-half pound of pressure against the grid strip 22. It is thus readily seen that the device thus described permits the strip 22 to be slidably maintained in a device and yet, through the action of the resilient members 50 and 60 holding the grid strip 22 against the fixed reference surfaces 42 and 44, any vibration of the strip 22 within the holding device is eliminated.

Although the invention has thus far been explained as being mounted on the rotary spindle of a lathe or other suitable grid winding machine, it has equal application as a stationary member through which a grid strip 22 is drawn. In this latter embodiment, the strip 22 is provided with only linear motion and the grid laterals are placed on the strip 22 through the utilization of a suitable winding head which rotates around the strip 22. Here, as before, the winding should take place at a point which is in close proximity to the free end of the support member 30.

While there have been shown and described what are

at present considered to be the preferred embodiments of the invention, modifications thereto will readily occur to those skilled in the art. It is not desired, therefore, that the invention be limited to the specific arrangement shown and described and it is intended to cover in the appended claims all such modifications as fall within the true spirit and scope of the invention.

I claim as my invention:

1. In a grid winding machine, a holding device for slidably retaining a frame grid strip having first and second side rods and a plurality of cross bars affixed to and maintaining said side rods in a spaced relationship comprising a support member having first and second fixed surfaces lying in planes substantially perpendicular to each other, first resilient means acting upon said first side rod to maintain said second side rod in slidable contact with said first fixed surface, and second resilient means acting simultaneously upon a plurality of said cross bars to maintain said grid strip in slidable contact with said second fixed surface.
2. In a grid winding machine, a holding device for slidably retaining a frame grid strip having first and second side rods and a plurality of cross bars affixed to and maintaining said side rods in a spaced relationship comprising a support member, first and second fixed surfaces on said support member against which said grid strip is slidably held, said fixed surfaces lying in planes substantially perpendicular to one another, recess means extending between said fixed surfaces whereby said surfaces do not meet, first resilient means acting upon said first side rod to maintain said second side rod in slidable contact with said first fixed surface, and second resilient means acting simultaneously upon a plurality of said cross bars whereby said grid strip is also maintained in slidable contact with said second fixed surface.
3. In a grid winding machine, a holding device for slidably retaining a frame grid strip having first and second side rods and a plurality of cross bars affixed to and maintaining said side rods in a spaced relationship comprising a support member, first and second fixed surfaces on said support member against which said grid strip is slidably held, said fixed surfaces lying in planes substantially perpendicular to each other, recess means extending between said fixed surfaces whereby said surfaces do not contact one another, said first fixed surface having a dimension transverse to the length of said grid strip not exceeding the diameter of said side rods, first means resiliently biased to act upon said first side rod to maintain said second side rod in slidable contact with said first fixed surface, and second means resiliently biased to act upon a plurality of said cross bars to maintain said grid strip in slidable contact with said second fixed surface.
4. In a grid winding machine, a holding device for slidably retaining a frame grid having first and second side rods and cross bars affixed to and maintaining said side rods in a spaced relationship comprising a support member, first and second fixed surfaces on said support member against which said grid strip is slidably held, said fixed surfaces lying in planes substantially perpendicular to each other, recess means extending between said fixed surfaces whereby said surfaces do not meet, said first fixed surface having a dimension transverse to the length of said grid strip which is less than the diameter of said side rods, first resilient means secured to said support member, means for biasing said first resilient means in a direction whereby said first resilient means acts upon said first side rod to maintain said second side rod in slidable contact with said first fixed surface, means for limiting the movement of said first resilient means, and second resilient means biased to act upon a plurality of said cross bars for maintaining said grid strip in slidable contact with said second fixed surface.
5. In a grid winding machine, a holding device for slidably retaining a frame grid strip having first and second side rods and a plurality of cross bars affixed to and

maintaining said side rods in a spaced relationship comprising a support member, first and second fixed surfaces on said support member against which said grid strip is slidably held, said fixed surfaces lying on planes substantially perpendicular to one another, recess means extending between said fixed surfaces whereby said surfaces do not meet, first resilient means acting upon said first side rod to maintain said second side rod in slidable contact with said first fixed surface, and second resilient means acting upon said grid strip in a direction substantially

perpendicular to said second fixed surface to maintain said grid strip in slidable contact with said second fixed surface.
